UNITED STATES PATENT OFFICE.

SIDNEY JOB POCOCK, OF ESHER, ENGLAND.

CAMP-BED AND COT OF THE COLLAPSIBLE TYPE.

1,176,926.

Specification of Letters Patent. Patented Mar. 28, 1916.

Application filed October 5, 1914. Serial No. 265,187.

To all whom it may concern:

Be it known that I, SIDNEY JOB POCOCK, knight, a subject of the King of Great Britain and Ireland, and resident of Esher, county of Surrey, England, have invented certain new and useful Improvements Relating to Camp-Beds and to Cots of the Collapsible Type, of which the following is a specification.

10 This invention relates to the general subject of camp beds, and more particularly to that type which are collapsible.

To this end the present invention contemplates a novel construction that may be 15 readily folded, and also dismembered if desired, to facilitate carriage and transportation, and which may also be readily assembled and prepared for use with a minimum expenditure of time and labor. In this connection, the invention proposes to provide 20 a construction that is light without sacrificing rigidity and strength when set up, and which also permits the use of a suitable shelter or protecting cover for the occupant, 25 preferably in the form of a net.

A further object of the invention is to provide a simple and substantial construction that is susceptible of a practical and economical commercial embodiment, and 30 which also provides a durable, neat and attractive bed device for camping or other purposes where a bed of this type is desirable.

With the above and other objects in view 35 which will more readily appear as the nature of the invention is better understood, the same consists in the novel construction, combination and arrangement of parts hereinafter more fully described, illustrated and 40 claimed.

A preferred and practical embodiment of the invention is illustrated in the accompanying drawings, in which—

Figure 1 is a side elevation of my improved collapsible bed in its open position. Fig. 2 is an end elevation thereof. Fig. 3 is an end elevation of the same in its collapsed or folded condition. Fig. 4 is a perspective view of the same in its open or extended condition.

Similar reference characters designate corresponding parts throughout the several figures of the drawings.

In carrying out the invention any suitable material may be utilized in constructing the framework, such for instance, as light

metal or wood, preferably the latter, and by reference to the several figures of the drawings, it will be observed that the invention essentially comprises the oppositely 60 located supporting elements which include the crossed leg members *a—a*. These leg members are preferably crossed at an intermediate point, and are connected by a longitudinally disposed tie rod *b*, the ends of 65 which form the fulcrum or bearing for the crossed leg members *a—a*. These latter members are preferably held to the said rod *b* by means of suitable fastening devices 70 *d* which will permit them to freely turn on the ends of the rod so that they may be readily brought from an open or extended position such as shown in Figs. 2 and 4 to the collapsed or closed position such as shown in Fig. 3, or vice versa. In addition 75 to the strength and rigidity imparted to the crossed leg members by the connecting rod, the said members *a—a* have other bracing elements at their upper ends. That is to say, the upper ends of each leg member *a* 80 at one end of the bed, are connected by means of a side frame member *c* with a corresponding leg member at the opposite end of the bed. Thus, the crossed leg members at each end of the bed are connected by the 85 parallel frame members *c*, which not only serve to strengthen and reinforce the entire structure, but also provide a convenient means for supporting a suitable bed receiving member *g*, which may be of canvas or 90 other like material, and suitably secured to the side frame members *c* by means of the lacings *h*, or the like.

Another novel and distinctive feature of the invention resides in the provision of 95 the net supporting struts *i*. These members are preferably pivotally carried by the tie rod *b* adjacent the crossing point of the leg members *a—a*, and not only make the entire bed more secure but are joined at their upper ends by means of a suitable cord *j* or other connecting member, to which a mosquito netting or like covering or shelter may be attached to protect the occupant.

From the foregoing, it is thought that the 105 manner of collapsing and opening up the bed will be readily apparent, and it will also be obvious that by the removal of the fastening elements *d* at the point of connection of the tie rod with the leg members, and 110 also at the point of connection of the side frame members *c* with the upper ends of the

leg members, the entire device may be taken down, and compactly and conveniently transported.

Without further description, it is believed 5 that the various features and advantages of the invention will be readily apparent, and it will of course be understood that changes in the form, proportion and minor details of construction may be resorted to 10 without departing from the scope of the invention or scope of the appended claim.

Having now described my invention, what I claim as new and desire to secure by Letters Patent of the United States is:—

15 A collapsible bed comprising oppositely located crossed leg members, a longitudinal

tie-rod forming a pivot for said legs and having means for securing the same thereto, side frame members connecting the upper corners of the oppositely located leg members and supporting a bed receiving member, vertically disposed net supporting struts located at each end of the bed receiving member and pivotally mounted on said longitudinal tie-rod, and a connecting member attached to the upper ends of said struts. 20 25

In testimony whereof I have affixed my signature in presence of two witnesses.

SIDNEY JOB POCOCK.
